(57) **CLAIM**

The ornamental design for a scoop net, as shown and described.

DESCRIPTION

FIG. 1 is an elevated perspective view of the scoop net; FIG. 2 is a declined perspective view of the scoop net depicted in FIG. 1;

FIG. 3 is a bottom view of the scoop net depicted in FIG. 1;

FIG. 4 is top view of the scoop net depicted in FIG. 1;

FIG. 5 is a front view of the scoop net depicted in FIG. 1;

FIG. 6 is a back view of the scoop net depicted in FIG. 1; and,

FIG. 7 is a left side view of the scoop net depicted in FIG. 1, where the right side view is a mirror image of FIG. 7.

The broken line showing of the scoop is for the purpose of illustrating the scoop mesh and forms no part of the claimed design.

1 Claim, 2 Drawing Sheets

FIG. 1

FIG. 2

FIG. 3
